To all whom it may concern:

Be it known that I, LEOPOLD SIMANDY, a citizen of the United States, residing at Colorado Springs, in the county of El Paso and State of Colorado, have invented and produced a new and original Design for a Tailor's Pick, of which the following is a specification, reference being had to the accompanying drawings, forming a part thereof.

Figure 1 is a side view of a tailor's pick embodying my new design. Fig. 2 is a plan view thereof. Fig. 3 is an end view.

As shown in the accompanying drawings, the leading or material feature of my design

consists in the handle 1, tapered to a point, 15 as at 1', and the jaws 2 2, rounded upon their outer sides, as at 3, and gradually tapered inward from the handle to their extremities 2' 2'.

Having thus fully described my design, what I claim, and desire to secure by Letters 20 Patent, is—
